UNITED STATES PATENT OFFICE

154,008

DESIGN FOR A PANTS HANGER

William Grant Williams, Anaheim, Calif.

Application December 1, 1947, Serial No. 142,907

Term of patent 14 years

(Cl. D33—8)

To all whom it may concern:

Be it known that I, William Grant Williams, a citizen of the United States, residing at Anaheim, in the county of Orange and State of California, have invented a new, original, and ornamental Design for Pants Hanger, of which the following is a specification, reference being had to the accompanying drawings, forming part thereof.

Fig. 2 is a view in side elevation, of the same;

Fig. 3 is a bottom plan view of the same;

Fig. 4 is a view in end elevation, of the same taken in the direction of the arrow 4 upon Fig. 2;

Fig. 5 is an end view in elevation of the same taken in the direction of the arrow 5 upon Fig. 2; and

Fig. 6 is a sectional view taken substantially upon the line 6—6 upon Fig. 2.

I claim:

The ornamental design for a pants hanger, as shown.

WILLIAM GRANT WILLIAMS.
